FIG. 2.

FIG. 3.

UNITED STATES PATENT OFFICE.

RICHARD LIEBAU, OF NEW HAVEN, CONNECTICUT, ASSIGNOR TO THE WESTINGHOUSE AIR SPRING COMPANY, A CORPORATION OF PENNSYLVANIA.

AIR-SPRING SUSPENSION.

1,410,933.

Specification of Letters Patent. Patented Mar. 28, 1922.

Application filed February 26, 1919. Serial No. 279,427.

To all whom it may concern:

Be it known that I, RICHARD LIEBAU, a citizen of the United States, and a resident of New Haven, in the county of New Haven and State of Connecticut, have made a new and useful Invention in Air-Spring Suspensions, of which the following is a specification.

This invention relates to vehicle air springs.

In mounting air springs on trucks and ambulances and in fact most of the vehicles in which the body overhangs the springs both front and rear it is desirable to place the air springs outside of the frame or load platform at positions approximately opposite the forward and rear ends of the forward and rear steel springs, respectively, and an object of this invention is to provide means for coupling up the air springs to the steel springs in vehicles having such overhanging bodies.

This, as well as other objects, I attain in the device described in the specification and illustrated in the drawings in which Figure 1 is a view in end elevation of the rear of an ambulance frame with the rear air springs installed in accordance with this invention.

Fig. 2 is a view similar to Fig. 1 of a portion of the front of the frame of the vehicle or ambulance showing one of the front springs installed in accordance with this invention and Fig. 3 is a view taken on line 3—3 of Fig. 1 looking in the direction of the arrow.

To each corner of the load platform or frame of the vehicle an air spring S having an outer guard cylinder 4, an inner telescoping cylinder 5 is mounted by means of a corner bracket 6 bolted or otherwise secured to the frame. The two air springs at one end of the vehicle have their cylinder bottoms connected by means of a cross brace or swivel. Each cross brace consists of a curved end 7 having an eye 8 whereby the cross brace is pivotally connected to the cylinder bottom by means of a pin 9. Each end member also is provided with a cylindrical portion 10 and at the juncture of the cylindrical portion 10 and the curved end portion a shoulder 11 is formed.

A sleeve 12 is shrunk onto the cylindrical portion adjacent shoulder 11 and is pinned thereto by means of pins 13. A tubular member 14 fits over the cylindrical ends of

the two end members, and the end members are forced apart by means of a coil spring 15 and a distance piece 16 both of which lie within the tubular member. The distance piece is preferably formed of wood for cheapness sake and the spring tends to hold the cylinder bottoms against the rear surfaces of the guard members 4. In the case of the rear air springs sleeve 13 is provided with an upstanding boss 17 which is drilled through from side to side to receive a shackle pin 18 and a shackle 19 connects boss 17 with the steel spring 20 by means of a spring bolt 21 which passes through the eye of the steel spring and the shackle. In case of the front suspension the shackle 19 is omitted and sleeve 13^a corresponding to sleeve 13 is provided with upstanding ears 22 between which the eye of steel spring 20^a is secured by means of a spring bolt 21^a.

In order to accommodate different widths of vehicles tubular member 14 may be cut to the desired length and the distance between spring 15 and the inner ends of the cylindrical ends 10 of the end members filled with a wooden block 16 cut accordingly.

Having thus described my invention what I claim is—

1. In combination with the load platform and steel springs of a vehicle, two pneumatic springs, each comprising two relatively movable telescopic members, means for securing one member of each spring to the load platform, a pivotal connection between the other member of each spring and one steel spring of the vehicle, and means located between said connections for yieldingly holding them apart.

2. In combination with the load platform and steel springs of a vehicle, two pneumatic springs, each comprising two relatively movable telescopic members, means for securing the outer member of each spring to the load platform, a pivotal connection between the inner member of each spring and one steel spring of the vehicle, and means extending below the load platform and engaging each pivotal connection and yieldingly forcing the inner telescopic members of the pneumatic springs laterally with relation to the outer telescopic members.

3. In combination with the load platform and steel springs of a vehicle, two pneumatic springs, each comprising two rela-

- 5 relatively movable telescopic members, means for securing one member of each spring to the load platform, a pivotal connection between the other member of each spring and one steel spring of the vehicle, a tubular member engaging both pivotal connections and provided with means for yieldingly forcing said connections outwardly with relation to the load platform.
- 10 4. In combination with the load platform and steel springs of a vehicle, two pneumatic springs, each comprising two relatively movable telescopic members, means for securing one of said telescopic members 15 of each spring to the load platform, a cross member extending below the load platform and forming a yielding connection between the other telescopic member of both springs, and means for connecting said cross member to said steel springs.

15 5. In combination with the load platform and steel springs of a vehicle, two pneumatic springs, each comprising an inner and outer telescopic member, means for se-

curing the outer member of each spring to 25 the load platform, a separate end member pivotally secured to the inner member of each spring, a shackle between said member and one steel spring of the vehicle, and yielding means between the end members 30 associated with both pneumatic springs.

6. In combination with the load platform and steel springs of a vehicle, two pneumatic springs, each comprising an inner and outer telescopic member, means for securing the 35 outer member of each spring to the load platform, a separate end member pivotally secured to the inner member of each spring and secured to one steel spring by a pin connection, and yielding means engaging 40 the end members associated with both pneumatic springs and yieldingly forcing them apart.

It testimony whereof, I have hereunto subscribed my name this 2nd day of December, 1918.

RICHARD LIEBAU.
